UNITED STATES PATENT OFFICE.

FRANCIS C. KOENIG, OF PHILADELPHIA, PENNSYLVANIA, ASSIGNOR TO
REINHOLD G. LEDIG, OF SAME PLACE.

DESIGN FOR A LAMP-BASE.

SPECIFICATION forming part of Design No. 22,443, dated May 16, 1893.

Application filed April 18, 1893. Serial No. 470,897. Term of patent 3½ years.

To all whom it may concern:

Be it known that I, FRANCIS C. KOENIG, a subject of the Emperor of Germany, (having resided one year last past in the United States 5 and declared my intention to become a citizen thereof,) residing in the city and county of Philadelphia, State of Pennsylvania, have invented and produced a new and original Design for the Base of a Lamp, of which the 10 following is a specification, reference being had to the accompanying drawing, forming part thereof.

The leading feature of my design for the base of a lamp, is the scroll configuration of 15 the same.

In the drawing: A designates the base of a

lamp, consisting of the top B, the middle part C, and the legs D. The top has lattice-work E thereon. The middle part consists of scrolls F, which face each other, and are joined at 20 top and bottom by the scrolls G and H. The legs D, D, are of the form of scrolls which join each other as at J, and have the scrolls H between them.

What I claim is—

The design for the base of a lamp, substantially as shown and described.

FRANCIS C. KOENIG.
